FUEL BURNER

Ervin G. Bailey, Easton, Pa., assignor, by mesne assignments, to The Babcock & Wilcox Company, Newark, N. J., a corporation of New Jersey

Application September 27, 1930, Serial No. 484,739
Renewed December 13, 1933

14 Claims. (Cl. 122—235)

This invention relates to a fuel burner that is especially adapted for projecting a plurality of flat thin streams or sheets of fuel and air into a furnace through spaces between water tubes located in a wall or arch of the furnace. The burner may be mounted and supported upon the water tubes.

The invention will be understood from the description in connection with the accompanying drawings, in which Fig. 1 is a vertical section through an illustrative embodiment of the invention; Fig. 2 is a section along the line 2—2 of Fig. 3; Fig. 3 is a section along the line 3—3 of Fig. 2; Fig. 4 is a view on an enlarged scale along the line 4—4 of Fig. 1; Fig. 5 is a section along the line 5—5 of Fig. 3, and Fig. 6 is a section along the line 6—6 of Fig. 2.

In the drawings, reference character 1 indicates a furnace above which a water tube boiler 2 of the Babcock & Wilcox type may be located.

Furnace wall tubes 3 may be provided along the walls of the furnace and lined with tile or the well-known Bailey blocks 4. These tubes are shown connected to lower headers 5 and upper headers 6 which may be connected to the water circulation system of the boiler in any of the well-known ways. The furnace floor 7, which is supported upon supports 8, is indicated as being of the type in which slag may collect thereupon and be tapped out at intervals.

A row of tubes 10 is shown connecting the front upper header 6 to a header 11, these tubes being lined with tile or Bailey blocks and shaped to form the furnace arch. The blocks or tile 12 may be kept in place on the tubes 10 by means of clamps 13, as indicated in Figs. 3 and 6 of the drawings.

The burner 14 is of the type in which the fuel can be injected into the furnace in a vertical direction and is connected to pipe 15. The pipe 15 may lead from a source of gas or other fuel, such as pulverized coal, for example, suspended in primary air. It will be observed that the burner has a plurality of outlets all in lateral alignment (see Fig. 4), and that these outlets are disposed between cooled members forming the furnace wall—as here illustrated, the tubes 10.

A mouth or exit device 16 is located at the end of the burner and is connected to the tubes 10. This device is shaped to divide the stream of gas or primary air and fuel into a plurality of thin parallel streams and project them through the spaces between the tubes 10 into the furnace. Flanges 17 are provided on the members 14 and 16 for convenience in connecting them together.

Brackets 18, which may be connected to the tubes 10 by means of bolts 19 connected to the tile, are provided for keeping the burner in place. The brackets 18 are connected to flanges 20 on the member 16.

A secondary air casing 21 surrounds the burner and a pipe 22 is connected thereto, which may provide preheated air for combustion purposes. A rod 23 provided with a turnbuckle for adjusting the length of this rod is located inside of the 10 casing 21 for connecting the outer end of the burner 14 to a bracket 23' that is attached to the tubes 10 to aid in supporting the burner.

The member 16 is provided with a plurality of hollow, transverse partitions or division members 15 24 somewhat wedge-shaped in cross-section (Figs. 3 and 6) and extending parallel to the tubes 10. These hollow partitions 24 are spaced apart to leave wedge-shaped openings 25 from the member 14 to the middle portion of the spaces between 20 the tubes 10. These openings 25 terminate in elongated mouths, as most clearly shown in Fig. 4, in the spaces midway between the tubes. Cross members 26 are provided at the enlarged ends of the hollow members 24 and have rounded depressions 27 to fit against the opposite surfaces of the tubes 10. Openings 28 are provided to permit secondary air from the casing 21 to enter the hollow partitions 24 from opposite directions.

As shown in Figs. 3 and 4, the air casing 21 extends beyond the ends of the nozzle series, and the tube blocks omitted in that area, leave unobstructed intertube ports between each end of the nozzle series and the adjacent casing wall. The end air ports thereby formed provide a slight excess of air at both ends of the burner. As shown in Figs. 2 and 4, the ends of the fuel nozzles do not extend the full length of the available intertube spaces, but terminate short thereof to leave openings above and below their discharge ends through which streams of excess air are discharged from the air casing 21. The curved deflector plates shown in Figs. 2 and 5 cause these air streams to impinge upon the opposite ends of each elongated fuel stream.

The operation is as follows: The stream of fuel and primary air entering the member 14 through the pipe 15 is narrowed in one direction and widened in a direction at right angles thereto as it enters the member 16 in a wide stream extending in a direction across the tubes 10. The widened stream is divided in the member 16 by the partitions 24 into a plurality of flat streams or sheets which pass through the spaces 25, becoming thinner until they pass out through the

outlet ends of the spaces 25 through the middle portion of the spaces between the tubes 10. These individual small flat streams or sheets are parallel to the tubes 10. At the same time, secondary air from the casing 21 enters the openings 28 over the edges of the cross members 26. The air entering each hollow member 24 escapes therefrom in two thin streams along opposite sides of the corresponding tube 10 in directions 10 at an angle to the center planes of the individual small sheets of primary air and fuel. In this way, each thin sheet of fuel and primary air is struck on opposite sides and end by streams of secondary air which causes each individual stream or sheet of fuel and primary air to be surrounded with secondary air just as they enter the furnace, so that the sheets of fuel and primary air do not come into contact with the surfaces of the tubes 10, being protected by the sheets or layers of 15 secondary air. The construction just described and illustrated is an example of one means associated with the burner to project sheets of secondary air between the burner outlets and the cooled members or tubes 10 in the furnace wall.

25 I claim:

1. In combination, a furnace having spaced tubes along a wall thereof, a burner means to project a plurality of sheets of fuel from said burner into said furnace and surround said sheets with secondary air, said means comprising V-shaped hollow members arranged in a series extending transversely of said tubes, and a combustion air casing around said burner, said hollow members being provided with openings therein into the space within said casing.

2. In a furnace, spaced cooled members forming a furnace wall, a burner carried by said members, a plurality of exit devices in said burner all in lateral alignment disposed with their discharge 40 opening between and spaced from said cooled members, and means associated with said burner to project sheets of combustion air between said discharge openings and said cooled members.

3. In a furnace, spaced cooled members forming a furnace wall, a burner disposed on the opposite side of said members from the combustion chamber of said furnace and having a plurality of laterally disposed exit nozzles divided into two groups, the nozzles of which are alternately spaced and one of said groups arranged to project its flow between the said members, and means associated with said burner to project primary air and fuel through one set of nozzles and secondary air through the other, said secondary air nozzles being constructed and arranged to project the secondary air between said primary air and fuel nozzles and the adjacent spaced cooled members.

4. In a furnace, spaced water tubes and a refractory covering thereon forming a furnace wall, a burner disposed on the opposite side of said water tubes from the combustion chamber of said furnace having a plurality of laterally disposed exit nozzles divided into two groups the nozzles of which are alternately spaced, one of said groups being arranged to project its flow between the water tubes, the refractory covering being omitted from the water tubes adjacent said burner, and means associated with said burner 60 to project primary air and fuel through one set of nozzles and secondary air through the other, said secondary air nozzles being constructed and arranged to project the secondary air between said primary air and fuel nozzles and the adjacent spaced cooled members.

5. In combination with a furnace a pulverized fuel nozzle for primary air and fuel mixture and passages for secondary air, comprising a flared body having an outlet of greater breadth than width, and approximately V-shape partitions disposed within and across said outlet with apices inwardly thereof and in spaced relation to each other to provide therebetween outlets for primary air and fuel, the inside walls of each partition forming passages for secondary air, the walls of each of said partitions being curved complementary to adjacent walls to provide streamline surfaces tending to preserve fluid velocity.

6. In a furnace, a water cooled wall, a fuel nozzle for primary air and fuel mixture and passages for secondary air all in said wall, said fuel nozzle comprising a flared body having an outlet of greater breadth than width, and approximately V-shape partitions disposed within and across said outlet with apices inwardly thereof and in spaced relation to each other to provide therebetween outlets for primary air and fuel, the inside walls of each partition forming passages for secondary air the walls of each of said partitions being curved complementary to adjacent walls to provide streamline surfaces tending to preserve fluid velocity.

7. In combination with a furnace wall having a fuel burner port formed therein and a row of cooling fluid tubes uniformly spaced across said burner port to form transversely spaced discharge openings therebetween, a fluid fuel burner comprising a series of transversely spaced nozzles adjacent to and spaced from said cooling tubes and discharging through said discharge openings, a combustion air casing at the outer side of said furnace wall and surrounding said burner port, and means for passing air from said casing through said burner port between each of the streams of fuel discharged from said nozzles and the corresponding adjacent cooling tubes.

8. In combination with a furnace wall having a fuel burner port formed therein and a row of cooling fluid tubes uniformly spaced across said burner port to form transversely spaced discharge openings therebetween, a fluid fuel burner comprising a fluid fuel conduit terminating in a series of transversely spaced nozzles adjacent to and spaced from said cooling tubes and discharging through said discharge openings, a combustion air casing at the outer side of said furnace wall and surrounding said burner port, and means for passing air from said casing through said burner port at opposite sides of each of the streams of fuel discharged from said nozzles and between said fuel streams and the corresponding adjacent cooling tubes.

9. In combination with a furnace wall having a fuel burner port formed therein and a row of cooling fluid tubes spaced across said burner port to form transversely spaced discharge openings therebetween, a fluid fuel burner comprising a fluid fuel conduit terminating in a series of transversely spaced nozzles adjacent to and spaced from said cooling tubes and discharging through said discharge openings, a combustion air casing at the outer side of said furnace wall and surrounding said burner port, and means for passing air from said casing through said burner port above and below the streams of fuel discharged from said nozzles and other streams between each of said fuel streams and the corresponding adjacent cooling tubes.

10. In combination with a furnace wall hav-

- ing a fuel burner port formed therein and a row of cooling fluid tubes uniformly spaced across said burner port to form transversely spaced discharge openings therebetween, a fuel burner 5 comprising a fluid fuel conduit terminating in a series of transversely spaced nozzles elongated longitudinally of and spaced from said cooling tubes and discharging through said discharge openings, a combustion air casing at the outer 10 side of said furnace wall and surrounding said burner port, and means for passing air from said casing through said discharge openings between each of the streams of fuel discharged from said nozzles and the corresponding adjacent 15 cooling tubes.
11. In combination with a furnace wall having a fuel burner port formed therein and a row of cooling fluid tubes uniformly spaced across said burner port to form transversely spaced discharge 20 openings therebetween, a fuel burner comprising a fluid fuel conduit having a fan-shaped distributing section terminating in a series of transversely spaced nozzles positioned between and spaced from said cooling tubes and 25 discharging through said discharge openings, a combustion air casing at the outer side of said furnace wall and surrounding said burner port, and means for passing air from said casing through said burner port between, each of the 30 streams of fuel discharged from said nozzles and the corresponding adjacent cooling tubes.
12. A fluid fuel burner comprising a distributing section progressively flaring in one direction and tapering in a direction normal thereto towards its discharge end and terminating in a 35 relatively short discharge section progressively flaring in said normal direction, and a series of hollow nozzle-forming members within and extending transversely of the direction of fuel discharge through said discharge section and spaced relative to each other and to the adjacent side walls of said discharge section to form nozzle passages therebetween opening at one end to said distributing section, each of said nozzle-forming members having an air chamber therein opening therefrom between the discharge ends of the nozzle 40 passages partly defined thereby.
13. A fluid fuel burner comprising a distributing section progressively flaring in one direction towards its discharge end and terminating in a relatively short discharge section progressively 10 flaring in a direction normal thereto, and a series of substantially V-shaped hollow nozzle-forming members within and extending transversely of the direction of fuel discharge through said discharge section and spaced relative to each other 15 to form nozzle passages therebetween opening at one end to said distributing section, each of said nozzle-forming members having an air chamber therein opening therefrom between the discharge ends of the nozzle 20 passages partly defined thereby.
14. A fluid fuel burner comprising a distributing section and terminating in a discharge section flaring towards its discharge end, and a series of substantially V-shaped hollow nozzle-forming members within and extending transversely of the direction of fuel discharge through said discharge section and spaced relative to each other and to the adjacent side walls of said 25 discharge section to form nozzle passages therebetween opening at one end to said distributing section, each of said nozzle-forming members having an air chamber therein opening therefrom between the discharge ends of the nozzle 30 passages partly defined thereby, and the walls of each of said nozzle-forming members being curved complementary to adjacent walls to provide streamline surfaces tending to preserve fluid 35 velocity.

ERVIN G. BAILEY.
